back into facial alignment with the remainder of the regenerated cellulose sheet;

Fig. 8 is a diagrammatic view illustrating one means for arranging the puncturings over desired areas in the regenerated cellulose sheet and for subsequently and simultaneously effecting the operation of rolling under pressure the tabs or flaps into facial alignment with the regenerated cellulose sheet; and

10 Fig. 9 is a fragmentary view in section of a container having steeping water therein and showing one of my improved packages in position therein.

Referring to the drawing and particularly Figs. 1 and 2, 10 designates a package or sack made 15 from regenerated cellulose and which may be in the form either transparent or translucent and which package or sack is filled with infusing material 11. Such material may be any desired, such as tea or coffee, and from which an infu- 20 sion is to be made by steeping in preferably hot water.

The package or sack 10 is made from regenerated cellulose in sheet form, such as the sheet illustrated in Fig. 3, and designated by the reference numeral 12. The sheet of material 12 is mechanically provided with puncturings 13, preferably arranged in groups and in any desired pattern and over designated areas of the sheet 12.

The puncturings, designated 13, are illustrated 30 in Figs. 4 to 7, inclusive, and are preferably made by a mechanical device such as is illustrated in Fig. 8.

The puncturings 13 may have any form desired, such as a curved form, illustrated in Figs. 35 3 and 4, to and including what may be termed practically substantially rectilinear slits. In making the puncturings 13, a cylinder 14, rotatably mounted on a shaft 15, is provided on its 40 surface with punch members 16 of the shape 13 of the puncturings desired to be made and which cooperates with an anvil 17 rotatably mounted on a shaft 18 parallel to the shaft 15. The cylinder 14 and anvil 17 run at the same peripheral speed, being constrained to do so by the inter- 45 meshing gears 19, mounted respectively on the shafts 15 and 17 and such gears, as well as the cylinder 14 and anvil 17, are of substantially the same diameter. The sheet 12 of regenerated cel- 50 lulose is passed through the space between the cylinder 14 and anvil 17 in the direction of the arrow shown in Fig. 8 and as a result, the tabs 20 of the puncturings 13 are forced outwardly from one side of the sheet 12 as shown in Figs. 5 and 6. The sheet of regenerated cellulose 12, 55 moving in the direction of the arrow shown in Fig. 8, brings the same into engagement with the parallelly arranged calendar rolls 21 rotatable each in the direction of the arrow shown, and which forces the flaps 20 back into the space 60 from which they came and into substantial facial alignment with the faces of the regenerated sheet 12. The sheet therefore has the appearance, after passing through the calendar rolls 21, as shown in Fig. 7, where the puncturings 13 can 65 be faintly discerned.

The flaps 20 are so arranged on the sheet of regenerated cellulose 12 and the sheet 12 is so manipulated during the making of the package or sack 10, that the flaps or tabs 20 will be forced 70 to curl up and extend into the interior of the bag or sack 10. This is clearly illustrated in Fig. 9, where the bag or sack 10 with the infusing material 11 therein, and being subjected to the action of the infusing water 22 held in the container 23, curls up under the action of the in- 75

fusing water, and is forced away from facial alignment with the sheet of material 12, into the inside of the bag or sack 10. The inward curling of the flaps or tabs 20 tends to prevent passage outward of the fine tea leaves into the infusing liquid 22.

The bag or sack 10 illustrated in Fig. 1 is made from the sheet 12 of regenerated cellulose by cutting from such sheet the material between the upper edge thereof and the lower edge and the two vertical lines designated by the reference numeral 24 in Fig. 3. This material with the groups of punctures 13, arranged as shown, is folded on the line 25 so as to bring the upper and lower edges into substantial alignment with each other, and a line of stitching started preferably at the point 26 on the line 25 is brought parallel to one of the lines 24, thence substantially parallel to the upper edge of the sheet, and then parallel to the other line 24, terminating again at the line 25. The line of stitching is designated by the reference numeral 27 in Figs. 1 and 2, and the sewing material at the termination of the line 27 is extended into a loop 28 and tied at its outer end to a designating tab 29. Before the last portion of the line of stitching 27 is completed, the bag or sack 10 is filled with the charge of infusing material 11, as shown in Fig. 12, and the completion of the last portion of the line of stitching 27 permanently closes 30 such infusing material within the bag or sack 10.

The designating tab 29 is preferably made from a sheet of regenerated cellulose and comprises a length of material substantially greater than the width of the bag 10, provided with parallel slits 30 to define a central portion 31 and side portions 32. This tab 29 is slipped onto the bag or sack 10 by having a central portion 31 arranged on one side of the sack and the side portions 32 arranged on the other side. Such tab 40 is also useful in the utilization of the package as it forms a convenient handle for putting the bag 10 into or taking the same out of the infusing water 22.

Whereas I have described my invention by reference to specific forms thereof, it will be understood that many changes and modifications may be made without departing from the spirit of the invention.

I claim:

1. An improved package for infusing material, said package being made from regenerated cellulose in sheet form provided with puncturings in desired group arrangement and size on designated areas of the material, the tabs resulting 55 from the stated puncturings being normally disposed in substantial facial alignment with the sheet, the punctured tabs being amenable to the action of infusing liquid, whereby said tabs curl to permit access of infusing liquid to the contents 60 of the package.

2. An improved package for infusing material made from a sheet of regenerated cellulose material, the package being in sack form and the material thereof provided with puncturings ar- 65 ranged in any desired grouping and size in the sheet of material, the tabs resulting from the stated puncturings being normally disposed in substantial facial alignment with the sheet of material and biased to open the puncturings and withdraw the tabs from the puncturings and into the interior of the package under action of infusing fluid.

3. An improved package for infusing material made from a sheet of regenerated cellulose ma- 75

5 terial in sack form such material having greater tensile strength in one direction than in the other, said sheet material being provided with puncturings arranged in any desired group formation, the length of such puncturings lying along the lines of greatest tensile strength of the material, the tabs resulting from the stated puncturings being normally disposed in substantial 10 facial alignment with the sheet of material and said tabs normally biased to curl or retreat from the sheet of the material upon exposure to infusing liquid and to retreat into the interior of the package to thereby open the puncturings.

10 4. An improved package for infusing material 15 made from a sheet of regenerated cellulose material in sack form such material having greater tensile strength in one direction than in the

other, said sheet material being provided with puncturings arranged in any desired group formation, the length of such puncturings lying along the lines of greatest tensile strength of the material, the tabs resulting from the stated puncturings being normally disposed in substantial 10 facial alignment with the sheet of material and said tabs normally biased to curl or retreat from the sheet of the material upon exposure to infusing liquid and to retreat into the interior of the package to thereby open the puncturings, and with the package closed by sewings of fibrous material and with the ends of fibrous material extending beyond the package and a tag attached to said ends.

15 CHRISTOPHER LUCKHAUPT.
